(57) **CLAIM**

The ornamental design for a polisher, as shown and described.

DESCRIPTION

FIG. 1 is top perspective view of a polisher showing our new design;

FIG. 2 is a bottom perspective view thereof;

FIG. 3 is a left side elevational view thereof;

FIG. 4 is a top plan view with portions broken away to fully disclose the claimed design;

FIG. 5 is a right side elevational view of FIG. 1;

FIG. 6 is a bottom plan view thereof;

FIG. 7 is a front elevational view thereof; and,

FIG. 8 is a rear elevational view thereof.

The broken lines in the figures depict portions of the polisher that form no part of the claimed design. The broken away symbols in FIG. 4 are shown to indicate the sections that are not shown. The broken away symbols form no part of the claimed design.
